EXPULSION FUSE

Alwin G. Steinmayer, Milwaukee, Wis., assignor
to Line Material Company, South Milwaukee,
Wis., a corporation of Delaware

Application September 24, 1936, Serial No. 102,293

14 Claims. (Cl. 200—117)

This invention relates to improvements in expulsion fuses for secondary electric circuits.

It is an object of this invention to provide for secondary circuits an expulsion type fuse comprising a cartridge adapted for attachment directly to a conductor and provided with a spring-actuated lever for removing the fuse link from the cartridge after the fusible section has blown.

More specifically, it is an object of this invention to provide a spring-actuated lever which will move the fuse link in a longitudinal direction relative to the cartridge and produce a minimum flexing action of the link as it moves to the exterior of the cartridge.

Another object is to provide a link-removing lever having means for clamping the link directly to the lever, to provide a spring-actuated lever to which a secondary conductor may be directly secured, to provide a spring-actuated lever to which a secondary conductor and fuse link may be secured in direct electrical contact with each other, and to provide a spring-actuated lever having a relatively flexible conductor secured thereto and provided with clamping means for connecting the flexible conductor with a secondary conductor.

A still further object is to provide a secondary fuse having a spring-actuated lever to which the flexible leader of a fuse link may be secured and from which this leader may extend for direct connection with a secondary conductor, thereby providing a minimum number of joints between the secondary conductors electrically connected by the fuse.

Another object is to provide a spring-actuated lever which will be protected against sleet, which is normally held in a biased position by means of the fuse link, and which is simple to manufacture and assemble.

Other advantages inherent in the novel invention herein disclosed will appear as the description proceeds.

In the drawings:

Fig. 1 is a view in side elevation, partly in section, illustrating an embodiment of this invention.

Fig. 2 is a lower end view of the device shown in Fig. 1.

Fig. 3 is a fragmentary view in side elevation, partly in section, taken on the line 3—3 of Fig. 1.

Fig. 4 is a fragmentary view in side elevation, partly in section, illustrating a modified form of this invention.

Fig. 5 is a lower end view of the device shown in Fig. 4.

Fig. 6 is a fragmentary view in side elevation, partly in section, illustrating a further modified form of this invention.

Fig. 7 is a view in side elevation illustrating a still further form of this invention.

Fig. 8 is a fragmentary view, partly in section, and taken on the line 8—8 of Fig. 1 showing the connector.

The device shown in Figs. 1, 2 and 3 comprises a cartridge or tube 1, preferably of fibrous material, having an upper ferrule or terminal 2 and a lower terminal or contact member 3, a closure cap 4 threaded on the ferrule and provided with a substantially rectangular stirrup 5 providing angularly related portions clearly shown in Fig. 1 and extending vertically therefrom, and a lever 6 pivotally mounted on the pin, which is secured to the lower terminal 3 laterally of the lower end of the tube 1.

The lever 6, as will be seen in Fig. 2, is U-shaped and is biased for movement downwardly relative to Fig. 1 by means of the spring 8 on the pin 7. As shown in Figs. 1 and 2, the lever 6 is provided on one of its arms with a lug 17 which is engaged by one end of the spring 8, the other end of the spring being engaged with the terminal 3. As will be seen from Figs. 1, 2 and 3, the lever 6 is held against downward movement by means of the fuse link 9 which extends beneath the lever 6 to the clamping nut 10 on the terminal 3.

Terminal or contact member 3 is provided with a substantially rectangular stirrup 11 providing angularly related portions clearly shown in Fig. 2 and extending in a horizontal plane laterally of the tube 1. A connector or clamping means 12 is mounted on each of the stirrups 5 and 11. These connectors are of a well known design, the generic structure of the connector 12, as indicated in Fig. 8, being disclosed in the patent to

W. D. Kyle et al., No. 2,095,098, issued October 5, 1937, for Connectors, in which bifurcated bolts straddle the stirrups and nut and jaw assemblies clamp the secondary conductor 13 and trans-

former lead-in wire 14 thereto to the stirrups 5 and 11 respectively. The conductor 13 and wire 14 may be connected as shown in Fig. 1 or

they may be connected to other side portions of the stirrups. These latter connections are not shown as they will be obvious and may be pre-

ferred only where angular relations of the conductor 13 and wire 14 suggest such connections.

The fuse link 9 is inserted in the tube 1 through the upper end of the ferrule 2 after the cap 4 is removed therefrom. The fuse link is

provided at its upper end with a flanged terminal 15 seated upon the ferrule 2 and with a fusible section 16. The spring 8 biases the lever 6 for movement away from the end of the tube 1 and thereby places the fusible section 16 of the fuse link under tension. When the fusible section is destroyed by a predetermined overload in the secondary circuit, the spring 8 through the lever 6 will move the lower remaining portion of the fuse link through the open lower end of the tube 1 and widely space the separated sections of the fuse link.

It will be obvious, from the disclosure in Figs. 1, 2 and 3, that, when the fusible section 16 has been destroyed, the fuse structure may be disconnected from the conductor 13 and wire 14 for the purpose of substituting a new fuse link for the destroyed one.

Preferably, the terminal 3 is provided at its lower end with a recess 18 within which the lever 6 is disposed. In view of the fact that the fuse structure is suspended in a substantially vertical position such as illustrated in Fig. 1, the sides of the recess 18 serve as a protecting apron for the lever 6, thereby preventing sleet from collecting about the lever 6.

In the modified form shown in Figs. 4 and 5, the upper end of the fuse structure may be similar to that disclosed in Fig. 1. However, in Figs. 30 4 and 5, the tube 1 is provided with a terminal 20 4 and 5, the tube 1 is provided with a terminal 20 having a downwardly extending pivot-supporting arm 21 spaced laterally of the tube. This arm 21 is provided with spaced lugs 21' supporting a pivot pin 23 upon which a lever 22 is pivotally mounted. A spring 24 biases the lever 22 for movement downwardly relative to the end of the tube 1. One end of the spring directly engages the lever 22 and the other end directly engages the arm 21.

The lever 22, shown in Figs. 4 and 5, is provided with an aperture 25 substantially coaxial with the bore of the tube 1 and with an aperture 26 normal to and intersecting the aperture 25. Registering with and extending into the intersecting portions of the apertures 25 and 26 is a clamping bolt 27. This bolt 27 clamps the fuse link 9 to the lever 22 and clamps the cable 28, which is preferably flexible, to the fuse link 9. As shown, the fuse link 9 extends through the aperture 25 and the cable 28 extends through the aperture 26. Thus we see that the line cable 28 is in direct contact with the fuse link 9.

When the fuse link 9, shown in Figs. 4 and 5, is destroyed in the manner previously indicated with reference to Fig. 1, the lever 22 will then be released for movement downwardly about the pivot 23, thereby pulling the fuse link 9 from the tube 1. Preferably, the cable 28 is flexible in order to allow the lever 22 to freely move about the pivot 23.

In Fig. 6, the tube 1 is provided with a terminal 30 having a recess 31 which houses the lever 32. The lever 32 is pivotally mounted within the recess 31 by means of the pin 33 and is biased for downward movement relative to Fig. 6 by means 65 of the spring 34 on the pivot 33. One end of the spring 34 directly engages the lever 32 and the other end of the spring directly engages the terminal 35.

The fuse link 9 extends downwardly through the aperture 35 in the lever 32 and is clamped to the lever by means of the clamping bolt 37. The lever 32 is provided with a flexible cable 38 which is soldered or otherwise secured to the lever at 38'. The cable 38 is provided at its lower end with a

bifurcated connector 39 commonly used by those skilled in the art. This connector 39 is permanently secured to the cable 38 and may be connected in the usual manner with a transformer lead-in wire, not shown. Thus, when the lever 32 shown in Fig. 6 is free to move downwardly, the flexible cable 38 will not seriously interfere with this movement.

In Fig. 7, the tube 1 is provided at its upper end with the structure illustrated in Fig. 1. In this view, the conductor 13 is illustrated as secured by means of a connector 42 to one of the side portions of the stirrup 5.

The lower end of the tube 1 is provided with a terminal 40 similar to that illustrated in Fig. 4. 15 This terminal is provided with an arm 21 supporting the pin 23 and upon which the lever 22 is pivotally mounted. This lever 22 is actuated downwardly relative to Fig. 7 by means of the spring 24 in the same manner as described with 20 reference to Fig. 4.

The fuse link 9 is secured to the lever 22 by means of the clamping bolt 27. This fuse link 9 extends from the lever and is secured by means of a bifurcated connector 42 to a terminal stud 40 on 25 the transformer 41, only a fragmentary transformer being illustrated. The fuse link is pulled from the tube 1 in the same manner as previously described with reference to the other figures and the flexible leader of the link 9 permits the lever 22 to freely move downwardly about its pivot.

Obviously, when the fuse link is to be replaced in the fuse illustrated in Fig. 7, the fuse will be disconnected from the conductor 13 and the flexible leader of the link 9 will be disconnected from the stud 40 on the transformer 41. The fuse link will then be disconnected from the lever 22 and the cap 4 will be removed from the tube 1 to permit a new link to be inserted in the tube. When the new link has been inserted, the cap 4 will be 40 replaced and the flexible end of the fuse link will be connected to the lever 22 as previously described. After the link has been assembled in the tube, the fuse will then be mounted as illustrated in Fig. 7.

In each of the modifications the link-removing lever is pivoted for movement in a path described by an arc extending from a tangent substantially parallel to the axis of the tube, thereby moving the fuse link from the tube with a minimum flexing thereof.

From the drawings and the foregoing description, it will be apparent that I have provided for secondary circuits an expulsion fuse in which a spring-actuated lever removes the fuse link from the fuse tube in a direction substantially longitudinally away from the end of the tube, thereby producing a minimum flexing of the fuse link as it moves from the tube and reducing resistance to such movement to a minimum.

It will also be seen that I have provided adequate protection for the movable parts of the fuse against interference from sleet, provided a minimum number of electrical connections between two secondary conductors, and provided a secondary expulsion fuse which is easily and cheaply manufactured and assembled.

I claim:

1. In combination with a first and a second electrical conductor, of an expulsion fuse comprising a cartridge open at one end and having a contact closing the other end and connected with the first conductor, a fuse link in said cartridge connected at one end with said contact, a spring-actuated lever pivotally supported by said car- 70

- tridge adjacent the open end thereof and having a pair of intersecting apertures, and a clamping bolt on said lever extending into said apertures at the intersection thereof, said link extending 5 through one of said apertures and the second conductor extending through the other aperture, said bolt holding said link in direct contact with said second conductor.
2. In combination with a first and a second 10 electrical conductor, of an expulsion fuse comprising a cartridge open at one end and having a contact closing the other end and connected with the first conductor, a fuse link in said cartridge connected at one end with said contact, a spring-actuated lever pivotally supported by said cartridge adjacent the open end thereof and having a pair of intersecting apertures, and a clamping bolt on said lever extending into said apertures at the intersection thereof, said link extending 15 through one of said apertures and the second conductor extending through the other aperture, said bolt holding said link in direct contact with said second conductor, said second conductor being flexible, thereby to offer a minimum resistance to 20 movement of said lever after said fuse link has blown.
3. A fuse structure including a cartridge open at one end, a contact closing the other end of said cartridge, a ferrule on said cartridge adjacent the open end thereof, said ferrule providing a hoodlike portion forming a recess at said open end, a lever pivotally supported by said portion for movement into said recess whereby to protect said lever from sleet, and a spring disposed 25 in said recess and urging said lever for movement out of said recess.
4. A fuse structure including a cartridge open at one end, a contact closing the other end of said cartridge, a ferrule on said cartridge adjacent the open end thereof, said ferrule comprising a hoodlike portion forming a recess at said open end, a lever pivotally supported by said portion for movement into said recess whereby to protect said lever from sleet, a spring disposed 30 in said recess and urging said lever for movement out of said recess, and a fuse link in said cartridge connected to said contact and having a flexible leader engaged with said lever and normally holding it in said recess.
5. In a fuse comprising a cartridge open at one 35 end and having a pair of contacts, one of which is disposed adjacent the open end of said cartridge and provided with a recess having a pair of coaxial apertures, and a fuse link in said cartridge connecting said contacts; a spring-actuated lever having a pivot pin in said apertures and biased for movement away from the open end of said cartridge, said lever being held within said aperture and adjacent to said open end by 40 said fuse link and said lever describing a downward arc relative to the open end of said cartridge upon blowing of the fuse link.
6. In a secondary fuse for electrically connecting electrically conductive wires, said fuse comprising a cartridge open at one end and having a pair of contacts, one of which is disposed adjacent the open end of said cartridge, and a fuse link in said cartridge connecting said contacts, said contact adjacent the open end of said cartridge being provided with a supporting arm; a spring-actuated lever pivotally mounted on said pivot-supporting arm, said lever being biased for movement upon blowing of said fuse link, each 45 of said contacts being provided with stirrups comprising a plurality of angularly related wire-en-
- gaging portions, and connector means on said stirrups for connecting said line wires thereto, said connector means being interchangeable between said wire-engaging portions.
7. In a fuse comprising a cartridge having an open end and a pair of contacts, and a fuse link in said cartridge connecting said contacts, one contact being disposed adjacent the open end of said cartridge and being provided with an inverted recess in registry with said open end; a 50 spring-actuated lever pivotally mounted in said recess, whereby to be protected from sleet, said spring-actuated lever being held in a biased position in said recess by said fuse link and describing an arc downward and away from the lower end of said open cartridge after said fuse link has blown.
8. In a fuse comprising a cartridge having an open end and a pair of contacts, and a fuse link in said cartridge connecting said contacts, one 55 contact being disposed adjacent the open end of said cartridge and being provided with an inverted recess in registry with said open end; a spring-actuated lever pivotally mounted in said recess, whereby to be protected from sleet, a flexible conductor secured to said lever and provided with means adapted to be connected with a conductor, clamping means on said lever securing said link thereto, said lever being held in a biased position in said recess by said fuse link and describing an arc downward and away from the lower end of said open cartridge after said fuse link has blown.
9. In an electric circuit, the combination with a conductor and transformer terminal, of a fuse 60 comprising a cartridge having an open end and a pair of contacts, and a fuse link including a flexible leader in said cartridge connecting said contacts, one of said contacts being detachably connected with said conductor and the other of said contacts being disposed adjacent the open end of said cartridge; a spring-actuated lever pivotally mounted on the last-mentioned contact, clamping means mounted on said lever and securing said flexible leader thereto, said leader extending from said lever and being in direct contact with said transformer terminal, said transformer terminal being remote from said cartridge, whereby movement of said lever is unhampered after the fuse link blows and said expulsion fuse will not cause strain on said conductor by reason of movement of the latter.
10. A secondary fuse comprising a cartridge having an open end and a pair of contacts, a fuse link in said cartridge connecting said contacts and having a flexible leader, one contact being disposed adjacent the open end of said cartridge, and a pivot pin on said one contact; a spring-actuated lever pivotally mounted on said pin and provided with clamping means for securing said leader directly to said lever, a second flexible leader secured at one end to said lever and provided at its other end with connector means, said second flexible leader being electrically connected with said flexible leader through said lever, said lever being adapted to effect removal of said fuse link.
11. In a fuse structure for direct connection with a conductor, the combination with a fuse tube, of a contact member on said tube, and 70 clamping means for connecting said member with said conductor, said member providing angularly related portions adapted to alternatively receive said means, whereby said conductor may be connected with said member in any one of a plurality 75

of angular relations to said tube substantially without distortion of said conductor.

12. In a fuse structure for direct connection with a conductor, the combination with a fuse tube, of a contact member on said tube comprising a stirrup having angularly related portions, and clamping means engageable alternatively with either of said portions for clamping said conductor to said stirrup in selective angular relations to said tube.
13. In a fuse structure for direct connection with a conductor, the combination with a fuse tube, of a closure cap closing one end of said

tube, a stirrup on said cap having angularly related portions, and clamping means engageable alternatively with either of said portions for clamping said conductor to said stirrup in selective angular relations to said tube.

14. A fuse cartridge comprising a fuse tube, a biased lever mounted thereon, and a fuse link in said tube, said cartridge including a flexible leader extending from said lever to a point remote from said cartridge, and clamping means for releasably connecting said fuse link with said lever, said leader being secured directly to said lever.

ALWIN G. STEINMAYER.
